UNITED STATES PATENT OFFICE.

HERBERT S. HUMPHREY, OF KALAMAZOO, MICHIGAN.

WATER-HEATER.

952,618.

Specification of Letters Patent. Patented Mar. 22, 1910.

Application filed November 23, 1908. Serial No. 464,121.

To all whom it may concern:

Be it known that I, HERBERT S. HUMPHREY, a citizen of the United States, residing at Kalamazoo, Kalamazoo county, Michigan, have invented certain new and useful Improvements in Water-Heaters, of which the following is a specification.

This invention relates to improvements in water heaters.

10 The main objects of this invention are: First, to provide in a water heater an improved valve mechanism whereby the temperature of the water may be effectively regulated by controlling the gas which is automatically turned on by the drawing off of the water. Second, to provide an improved valve mechanism for the automatic control of water heaters in which the heating means comprises a gas burner which 15 may be very accurately regulated and the overheating of the water, or of the heater, when water is being drawn off, or when the drawing off of the water ceases, is effectively prevented. Third, to provide an improved 20 valve mechanism which is comparatively simple and economical in structure and is not likely to get out of repair in use.

Further objects, and objects relating to structural details, will definitely appear 25 from the detailed description to follow.

I accomplish the objects of my invention by the devices and means described in the following specification.

The invention is clearly defined and 30 pointed out in the claims.

A structure embodying the features of my invention is clearly illustrated in the accompanying drawing, forming a part of this specification, in which,—

40 Figure 1 is a detail side elevation of a structure embodying the features of my invention. Fig. 2 is a detail horizontal section, taken on a line corresponding to line 2—2 of Fig. 1, showing details of the valve mechanism. Fig. 3 is an enlarged detail 45 vertical section, taken on a line corresponding to the broken line 3—3 of Fig. 1. Fig. 4 is a detail vertical section, taken on a line corresponding to line 4—4 of Fig. 2. Fig. 5 is a further detail vertical section, taken 50 on a line corresponding to the broken line 5—5 of Fig. 3. Fig. 6 is an enlarged detail section taken on a line corresponding to line 6—6 of Fig. 3, showing the arrangement 55 of the valves for the pilot.

In the drawing, the sectional views are

taken looking in the direction of the little arrows at the ends of the section lines, and similar numerals of reference refer to similar parts throughout the several views. 60

Referring to the drawing, the heater 1 illustrated is preferably of the coil type, the coils 2 being arranged within the heater casing, which is preferably double walled, as illustrated, to prevent radiation. The 65 gas burners 3 are located below the water coils. The cold water is delivered to the upper end of the coils through the inlet valve casing 4, which is provided with a cold water inlet 5 and a cold water discharge 6, the inlet 5 being connected to the water supply and the discharge 6 being connected to the inlet pipe 7 at the upper end of the heater coils. The valve casing is also provided with a hot water inlet 8 and 70 a discharge 9, the hot water inlet 8 being connected to the delivery pipe 10 of the heater coils, preferably through the thermostat tube 11. The hot water inlet is connected to the cold water discharge by means 75 of the circulation port 12, so that, when the circulation port 12 is opened, the water may circulate through the water coils and the thermostat. The hot water discharge 9 is connected to the house system, or to the 80 draw-off faucet 13, the faucet being illustrated for convenience. The hot water discharge 9 is controlled by the valve 14, which regulates the amount of water passing through the heater. The water inlet valve 90 15 is preferably of the piston type, and is adapted to be automatically opened by the pressure of the inlet water when the draw-off faucet is opened, thereby reducing the pressure within the heater or system. On 95 the stem 16 of the valve 15 I arrange a circulation valve 17. This circulation valve 17 is loosely mounted on the stem and is yieldingly held against the rest 18 by means of the spring 19. This spring 19 is preferably a coiled spring, arranged about the stem, its upper end bearing against the valve 15, and its lower end engaging the circulation valve 17. The rest 18 is preferably made adjustable, so that the valve 17 seats 100 at the desired point prior to the opening of the inlet valve 15. A further advantage of this adjustment is that it obviates the necessity for great care in manufacturing and fitting the parts. On the section 20 of the 105 water inlet valve stem 16 and projecting outwardly from the valve, I arrange a return

spring 21. This return spring 21 is compressed by opening the valve 15, and expands to return it to its seat. The spring is arranged in a chamber 22, which is in the form of a cylindrical cap-like extension in the valve casing, and which cap can be removed without removing the main cap of the valve casing. This permits the adjustment or the renewal of the spring 21 without disturbing the packing for the main cap. The gas valve casing 23 is provided with an inlet 24 which is connected to the gas supply 25 and the discharge 26, which is connected by the pipe 27 to the burners. The pipe 27 is preferably provided with a valve 28 by which the delivery of the gas to the burners may be cut off entirely, if desired.

The delivery of the gas is controlled by the valves 29 and 30, the valve 29 being the main gas valve and controlling the inlet passage, and the valve 30 being an auxiliary valve and adapted to control the outlet of the gas. The valve 29 is arranged to be controlled by the water inlet valve 15, the stem 31 of the main gas valve 29 being arranged so as to be engaged by the stem 16 of the water inlet valve, so that, when the water inlet valve is opened, the gas valve 29 is opened. The gas valve is returned to its seat by the spring 32. The valve 30 is controlled by the thermostat, which is arranged in the thermostat tube 11, connected to the heater and to the valve casing, as previously stated. This thermostat preferably consists of the tubular member 33, which is connected at its upper end to the valve casing 4, as clearly appears in Figs. 4 and 5, and depends into the thermostat tube 11, as illustrated in Fig. 3. Within the member 33 is a rod-like thermostat member 34, which is not connected at its lower end to the member 33. The upper end of the thermostat member 34 is arranged to act on the lever 35, which is fulcrumed at 36 upon the water valve casing, the water valve casing being provided with a chamber 37, (see Fig. 5) adapted to receive the inner end of the lever 35. The fulcrum 36 is preferably threaded, as illustrated, so that it may be adjusted to properly adjust the parts. The lever 35 is arranged horizontally and adapted to act on the vertically-arranged lever 38, which is fulcrumed at 39 on the gas valve casing. The lever 38 is secured by means of the pivot 40 to the stem 41 of the valve 30, so that when the thermostat is actuated by the changes in temperature of the water, the gas valve 30 is actuated. The gas valve 30 is held yieldingly closed by means of the coiled spring 42. By this arrangement of the valves, when the drawing off of the water is stopped the water inlet valve automatically closes and the gas valve 29 normally closes, but should the gas valve for

any reason fail to close, the gas is cut off by the thermostatically-controlled valve 30 as the water in the heater soon becomes hot enough to actuate the thermostat. The valve 30 also serves to keep the temperature of the water drawn from the heater at a fairly even temperature. The thermostat tubes and member and the lever 35 being mounted upon and supported from the valve casing 4, the proper relations of the parts are maintained and it is quite unlikely that they should be disarranged either from the settling of the parts or from carelessness in assembling sufficient to interfere with the efficient working thereof.

The gas and water valve casings are preferably made separately and connected by a yoke 43 by which they are held in proper position, the valves otherwise being supported upon the connecting pipes, which, in practice, I find entirely practicable. Each valve casing is preferably made up of a plurality of parts for convenience in manufacture, but, as these details will be readily understood by one skilled in this art, from an inspection of the drawings, I have not described them specifically.

I preferably provide a gas cut off valve 44, which is interposed between the valves 29 and 30. This valve 44 is principally intended for use when the heater is out of operation,—that is, if it is not to be used for a considerable period of time, it is desirable to cut off the gas, thereby preventing any possibility of leakage in the heater, or otherwise. The delivery pipe 10 of the heater is also preferably provided with a valve, as 45, which may be used for cutting off the flow of water entirely, or for adjusting the same. In practice, it is not intended that this valve 45 shall be manipulated after the heater is properly adjusted.

The pilot 46 is connected by the pipe 47 to the passage 48 in the valve casing, which is connected by the by-pass 49, and through the valve 50, to the gas supply or inlet passage 24,—see Fig. 6. The by-pass 49, through which the normal supply of gas is delivered, is controlled by the needle valve 51, thereby regulating the size of the normal pilot flame. When the water inlet valve acts upon the valve 29 to open the same, the valve 50 is opened, thereby flashing the pilot by delivering an additional supply of gas through the passage 48 and to the pilot. The pilot is also preferably provided with a cut-off valve as 52.

By thus arranging the parts, I control the heater automatically,—that is, the delivery of gas thereto, and the overheating of the heater is positively prevented.

I have illustrated and described my improved water heater in detail in the form preferred by me on account of its structural simplicity and economy, and the convenience

with which the parts may be assembled. Further, on account of the durability of the same, and that it is not likely to get out of repair. I am aware, however, that my invention is capable of considerable variation in structural details without departing from my invention, and I desire to be understood as claiming the same broadly as well as specifically.

10 Having thus described my invention, what I claim as new and desire to secure by Letters Patent is:—

1. The combination with a water heater, of a gas burner therefor; a water valve casing having a cold water inlet and discharge, a hot water inlet and discharge, and a circulation port connecting said hot water inlet with said cold water discharge, said cold water discharge and said hot water inlet being connected to the water heater; a water inlet valve; a return spring for said inlet valve; a circulation valve arranged to be automatically controlled by said inlet valve whereby it is closed when said water inlet valve is open, and opened when said water inlet valve is closed; a valve for controlling said hot water discharge; a thermostat connected to said heater; a gas valve casing having an inlet and a discharge passage, said discharge passage being connected to said burner; valves for controlling said inlet and discharge passages, said inlet valve being arranged to be controlled by said water inlet valve and said discharge valve being controlled by said thermostat; and a cut-off valve interposed between said valves for said inlet and discharge passages.

2. The combination with a water heater, of a gas burner therefor; a water valve casing having a cold water inlet and discharge, a hot water inlet and discharge, and a circulation port connecting said hot water inlet with said cold water discharge, said cold water discharge and said hot water inlet being connected to the water heater; a water inlet valve; a return spring for said inlet valve; a circulation valve arranged to be automatically controlled by said inlet valve whereby it is closed when said water inlet valve is open, and opened when said water inlet valve is closed; a thermostat connected to said heater; a gas valve casing having an inlet and a discharge passage, said discharge passage being connected to said burner; valves for controlling said inlet and discharge passages, said inlet valve being arranged to be controlled by said water inlet valve and said discharge valve being controlled by said thermostat; and a cut-off valve interposed between said valves for said inlet and discharge passages.

3. The combination with a water heater, of a gas burner therefor; a water valve casing having a cold water inlet and discharge, a hot water inlet and discharge, and a cir-

culation port connecting said hot water inlet with said cold water discharge, said cold water discharge and said hot water inlet being connected to the water heater; a water inlet valve; a return spring for said inlet valve; a circulation valve arranged to be automatically controlled by said inlet valve whereby it is closed when said water inlet valve is open, and opened when said water inlet valve is closed; a valve for controlling said hot water discharge; a thermostat connected to said heater; a gas valve casing having an inlet and a discharge passage, said discharge passage being connected to said burner; and valves for controlling said inlet and discharge passages; said inlet valve being arranged to be controlled by said water inlet valve and said discharge valve being controlled by said thermostat.

4. The combination with a water heater, of a gas burner therefor; a water valve casing having a cold water inlet and discharge, a hot water inlet and discharge, and a circulation port connecting said hot water inlet with said cold water discharge, said cold water discharge and said hot water inlet being connected to the water heater; a water inlet valve; a return spring for said water inlet valve; a circulation valve arranged to be automatically controlled by said inlet valve whereby it is closed when said water inlet valve is open, and opened when said water inlet valve is closed; a thermostat connected to said heater; a gas valve casing having an inlet and a discharge passage, said discharge passage being connected to said burner and valves for controlling said inlet and discharge passages, said inlet valve being arranged to be controlled by said water inlet valve and said discharge valve being controlled by said thermostat.

5. The combination with a water heater, of a gas burner therefor; a water valve casing having a cold water inlet and discharge, a hot water inlet and discharge, and a circulation port connecting said hot water inlet with said cold water discharge, said cold water discharge and said hot water inlet being connected to the water heater; a water inlet valve; a circulation valve arranged to be automatically controlled by said inlet valve whereby it is closed when said water inlet valve is open, and opened when said water inlet valve is closed; a valve for controlling said hot water discharge; a thermostat connected to said heater; a gas valve casing having an inlet and a discharge passage, said discharge passage being connected to said burner; valves for controlling said inlet and discharge passages, said inlet valve being arranged to be controlled by said water inlet valve and said discharge valve being controlled by said thermostat; and a cut-off valve interposed between said valves for said inlet and discharge passages.

6. The combination with a water heater, of a gas burner therefor; a water valve casting having a cold water inlet and discharge, a hot water inlet and discharge, and a circulation port connecting said hot water inlet with said cold water discharge, said cold water discharge and said hot water inlet being connected to the water heater; a water inlet valve; a circulation valve arranged to be automatically controlled by said inlet valve whereby it is closed when said water inlet valve is open, and opened when said water inlet valve is closed; a thermostat connected to said heater; a gas valve casing having an inlet and a discharge passage, said discharge passage being connected to said burner; valves for controlling said inlet and discharge passages, said inlet valve being arranged to be controlled by said water inlet valve and said discharge valve being controlled by said thermostat; and a cut-off valve interposed between said valves for said inlet and discharge passages.
7. The combination with a water heater, of a gas burner therefor; a water valve casting having a cold water inlet and discharge, a hot water inlet and discharge, and a circulation port connecting said hot water inlet with said cold water discharge, said cold water discharge and said hot water inlet being connected to the water heater; a water inlet valve; a circulation valve arranged to be automatically controlled by said inlet valve whereby it is closed when said water inlet valve is open, and opened when said water inlet valve is closed; a valve for controlling said hot water discharge; a thermostat connected to said heater; a gas valve casing having an inlet and a discharge passage, said discharge passage being connected to said burner; and valves for controlling said inlet and discharge passages, said inlet valve being arranged to be controlled by said water inlet valve and said discharge valve being controlled by said thermostat.
8. The combination with a water heater, of a gas burner therefor; a water valve casting having a cold water inlet and discharge, a hot water inlet and discharge, and a circulation port connecting said hot water inlet with said cold water discharge, said cold water discharge and said hot water inlet being connected to the water heater; a water inlet valve; a circulation valve arranged to be automatically controlled by said inlet valve whereby it is closed when said water inlet valve is open, and opened when said water inlet valve is closed; a thermostat connected to said heater; a gas valve casing having an inlet and a discharge passage, said discharge passage being connected to said burner; and valves for controlling said inlet and discharge passages, said inlet valve being arranged to be controlled by said
- water inlet valve and said discharge valve being controlled by said thermostat.
9. The combination with a water heater, of a gas burner therefor; a water valve casting having a cold water inlet and discharge, a hot water inlet and discharge, and a circulation port connecting said hot water inlet with said cold water discharge, said cold water discharge and said hot water inlet being connected to the water heater; a water inlet valve; a circulation valve arranged to be automatically controlled by said inlet valve whereby it is closed when said water inlet valve is open, and opened when said water inlet valve is closed; a thermostat arranged in said connection for said heater to said hot water inlet; a gas valve casing having an inlet and a discharge passage, said discharge passage being connected to said burner; valves for controlling said inlet and discharge passages, said inlet valve being arranged to be controlled by said water inlet valve and said discharge valve being controlled by said thermostat.
10. The combination with a water heater, a water valve casing having therein a cold water inlet and discharge, a hot water inlet and discharge, and a circulation port connecting said hot water inlet with said cold water discharge, said hot water inlet and said cold water discharge being connected to the water heater, whereby, when said circulation port is open, water may circulate through said heater valve casing and said heater connections therefor; a water inlet valve; and a circulation valve arranged to be automatically controlled by said water inlet valve whereby it is closed when said water inlet valve is open, and opened when said water inlet valve is closed.
11. The combination with a water heater, of a gas burner therefor; a water valve casting having a cold water inlet and discharge, a hot water inlet and discharge, and a circulation port connecting said hot water inlet to said cold water discharge said cold water discharge and said hot water inlet being connected to the water heater; a piston water inlet valve; a stem therefor; a return spring for said inlet valve; a circulation valve for said port loosely mounted on the stem of said water inlet valve; an adjustable rest for said circulation valve on said stem; a coiled spring arranged on said stem to engage said valve for holding it yieldingly against its said rest whereby said circulation valve is automatically closed when said water inlet valve is opened; a gas valve; a stem therefor arranged to be engaged by the stem of said water inlet whereby said gas valve is opened by said water inlet valve; and a return spring for said gas valve.
12. The combination with a water heater, of a gas burner therefor; a water valve cas-

ing having a cold water inlet and discharge, a hot water inlet and discharge, and a circulation port connecting said hot water inlet to said cold water discharge, said cold water discharge and said hot water inlet being connected to the water heater; a piston water inlet valve; a stem therefor; a return spring for said inlet valve; a circulation valve for said port loosely mounted on the stem of said water inlet valve; a rest for said circulation valve on said stem; a coiled spring arranged on said stem to engage said valve for holding it yieldingly against its said rest whereby said circulation valve is automatically closed when said water inlet valve is opened; a gas valve; a stem therefor arranged to be engaged by the stem of said water inlet valve whereby said gas valve is opened by said water inlet valve; and a return spring for said gas valve.

13. The combination with a water heater, a water valve casing having a cold water inlet and discharge, a hot water inlet and discharge, and a circulation port connecting said hot water inlet to said cold water discharge, said cold water discharge and said hot water inlet being connected to the water heater; a piston water inlet valve; a stem therefor; a return spring for said inlet valve; a circulation valve for said port loosely mounted on the stem of said water inlet valve; an adjustable rest for said circulation valve on said stem; and a coiled spring arranged on said stem to engage said valve for holding it yieldingly against its said rest whereby said circulation valve is automatically closed when said water inlet valve is opened.

14. The combination with a water heater, of a water valve casing having a cold water inlet and discharge, a hot water inlet and discharge, and a circulation port connecting said hot water inlet to said cold water discharge, said cold water discharge and said hot water inlet being connected to the water heater; a piston water inlet valve; a stem therefor; a return spring for said inlet valve; a circulation valve for said port loosely mounted on the stem of said water inlet valve; a rest for said circulation valve on said stem; and a coiled spring arranged on said stem to engage said valve for holding it yieldingly against its said rest whereby said circulation valve is automatically closed when said water inlet valve is opened.

15. The combination with a water heater of a burner therefor; a water inlet valve; a stem therefor; a circulation valve loosely mounted on the stem of said water inlet valve; an adjustable rest for said circulation valve on said stem; a spring for holding it yieldingly against its said rest whereby said circulation valve is automatically

closed when said water inlet valve is opened; a gas valve; and a stem therefor arranged to be engaged by the stem of said water inlet valve whereby said gas valve is opened by said water inlet valve.

16. The combination with a water heater, of a burner therefor; a water inlet valve; a stem therefor; a circulation valve loosely mounted on the stem of said water inlet valve; a rest for said circulation valve on said stem; a spring for holding it yieldingly against its said rest whereby said circulation valve is automatically closed when said water inlet valve is opened; a gas valve; and a stem therefor arranged to be engaged by the stem of said water inlet valve whereby said gas valve is opened by said water inlet valve.

17. The combination with a water heater of a gas burner therefor; a water valve casing having a cold water inlet and discharge, a hot water inlet and discharge, and a circulation port connecting said hot water inlet with said cold water discharge, said cold water discharge and said hot water inlet being connected to the water heater; a water inlet valve; a circulation valve arranged to be automatically controlled by said inlet valve whereby it is closed when said water inlet valve is opened, and opened when said water inlet valve is closed; a thermostat arranged in said connection for said heater to said hot water inlet; a gas valve casing; a gas valve; and connections for said thermostat to said gas valve comprising a lever pivoted on said water valve casing arranged to be actuated by a member of the thermostat, and a lever pivoted on said gas valve arranged to be actuated by said lever pivoted on said water valve, said lever on said gas valve casing being connected to said gas valve.

18. The combination with the water heater of a water valve casing connected to a heater, of a thermostat arranged in said connection; a gas valve casing; a gas valve; and a connection for said thermostat to said gas valve comprising a lever fulcrumed on said water valve casing and arranged to be acted upon by said thermostat, and a lever fulcrumed on said gas valve casing arranged to be actuated by said lever actuated by said thermostat, said lever being connected to the gas valve.

In witness whereof, I have hereunto set my hand and seal in the presence of two witnesses.

HERBERT S. HUMPHREY. [L. S.]
